FIG. 5

INVENTOR

W. A. Robertson.

BY

C. F. Henkel.

ATTORNEY

UNITED STATES PATENT OFFICE.

WILLIAM A. ROBERTSON, OF CLEVELAND, OHIO.

HEADLIGHT.

Application filed May 5, 1922. Serial No. 558,693.

To all whom it may concern:

Be it known that I, WILLIAM A. ROBERTSON, a citizen of the United States, and resident of Cleveland, county of Cuyahoga, and

5 State of Ohio, have invented a new and useful Improvement in Headlights, of which the following is a specification.

My invention relates to headlights generally and to electrically illuminated headlights particularly.

10 The object of my invention is an efficient headlight adapted to emit illumination either in the form of a beam of light, or of diffused light, or of both, and to confine sub-

15 stantly all of this illumination below a plane on a level with the top of the headlight.

I attain this object by mounting a plurality of reflectors, of certain formation, in certain relations with two lamps, of substantially equal candle-power, as distinguished from the usual dim or pilot light and the bright lights, and by a switch arrangement which permits the illumination of either of 20 the lamps separately or of both simultaneously.

My invention is illustrated in the accompanying drawing which shows a headlight constructed according to the present invention and in which Fig. 1 is a general side view showing a headlight and switch; Fig. 2 is a section of Fig. 3 showing clearly the arrangement of two lamps in relation with a main reflector and a sub-reflector and a hood reflector, Fig. 3 is a front end view of Fig. 1, Fig. 4 is a section of Fig. 3, showing a flat subreflector, and Fig. 5 is a section taken similar to Fig. 4, showing a curved subreflector.

25 40 Similar reference characters refer to similar parts throughout the views.

The glare of headlights, particularly on automobiles and other vehicles, is objectionable since it blinds drivers going in opposite directions.

45 In order to eliminate this glare, the glass of the headlights has been treated in some manner, such as painting or frosting, but such treatment necessarily weakens the illuminating power of the headlights, resulting in low efficiency.

The present invention aims to utilize substantially all of the light emitted by the lamps and direct it out of the headlight as aforesaid.

55

Referring now particularly to the drawing,

The case A, open at the front end and obliquely dented in the lower front end, is provided with the lamp sockets 10 and 11 into which the lamps 12 and 13 fit.

60

The main reflector R, highly polished on the inside, is mounted in the case A and also has provisions to accommodate the sockets 10 and 11.

65

The main reflector R is of concave contour with a substantially circular front end interrupted, at the bottom, by a portion thereof being cut away obliquely in conformity to the dented portion of the case A.

70

The lamp 12 is mounted in the socket 10 and makes the usual electrical connection therein and has its center of illumination located on the axis of the reflector R.

75

The lamp 13 is mounted in the socket 11 and makes the usual electrical connections therein and is, in this instance, located above and ahead of the lamp 12 but within the boundaries of the main reflector R.

80

The subreflector B is secured to the obliquely dented portion of the case A and covers the cut away portion of the reflector R and is highly polished or otherwise prepared on the inside to act as a reflector.

85

The formation of this reflector B may be flat as shown in Figs. 1 and 4, or curved as shown in Fig. 5.

90

The flat formation of the reflector B shown in section in Fig. 2 produces better diffused illumination while the curved formation thereof produces better beam illumination.

95

The sub-reflector B is either flat throughout or curved (as shown in Fig. 5) conforming to the dented portion of the case A and faces the main reflector R.

100

The cover C is hinged to the case A by means of the hinges 14 and has the curved glass 15 held in the frame 16 and closes the open front end of the case A.

The hood 17 of the cover C comprises a reflector shield, concave in contour, covering

the lamp 13 and the upper portion of the main reflector R from view and redirecting downwardly the upwardly directed rays from both of the lamps 12 and 13 and from 5 the main reflector R.

The lugs 18 are provided on the case A to permit the headlight to be mounted readily.

The operation of this headlight is as follows:

- 10 When the switch arm 19, shown in neutral in Fig. 1, is rotated right handed to the first contact stop 20, electric current flows from the battery 21 to the arm 19 and to the contact 20, then to the lead 22, then through the 15 lamp 12, and then back to the battery through the ground 23.

The lamp 12 is now emitting light rays in all directions, some of them directly forward and out through the glass 15, others impinging upon the reflector R, and others upon the reflector B, and others upon the inside of the hood 17. Some of the rays, which impinge upon the reflector R, are deflected out through the glass 15, others are

- 25 reflected upon the reflector B, and others upon the inside of the hood 17. Some of the rays, which impinge upon the reflector B, are reflected upon the reflector R where they again are reflected either out through the glass 15 or upon the inside of the hood 17, other rays are reflected upon the inside of the hood 17 where they again are reflected either outward or downward, or upon the reflector R where they are again reflected as stated. Some of the rays which impinge upon the inside of the hood 17 are reflected outward and downward, and others are reflected upon the reflector R where they are again reflected as stated and others upon the 35 reflector B where they are again reflected as stated.

The requirement of the present invention is that all, or nearly all, of the light rays emitted by the lamp 12 are directed straight 45 out through the glass 15 and the curvatures and the disposition of the deflectors should be arranged to accomplish this requirement.

The rays of light emitted by the lamp 12 and passing directly out through the glass 50 15, and the rays reflected directly out through the glass by the reflector R, have the same general direction and constitute or form a beam of light straight ahead.

When the arm 19 is rotated further, in 55 right handed direction, and to the second contact stop 26, electric current flows from the battery 21 to the arm 19 and to the contact 26, then to the lead 27, then through the lamp 13, and then back to the battery 60 through the ground 23.

The lamp 13 is now emitting light rays in all directions, some of them directly forward and downward and out through the glass 15, others impinging upon the reflectors R and B, and others upon the hood 17. Due to the

off focus disposition of the lamp 13, these impinging rays are reflected so that they do not collect as a beam of light but so that they leave the headlight as a diffused light.

When the arm 19 is rotated further, in 70 right handed direction and to the third contact stop 30, electric current flows from the battery 21 to the arm 19 and the contact 30, then to the lead 27, then through the lamp 13, and then back to the battery through 75 the ground 23. At the same time, electric current flows from the battery 21 to the contact 31, then to the lead 32, then through the lamp 12, and then back to the battery through the ground 23. 80

Both of the lamps 12 and 13 are now illuminated and the headlight emits a beam of light due to the lamp 12, and a diffused light due to the lamp 13.

With this switch arrangement, either a 85 beam of light (contact 20) or a diffused light (contact at 26) or a combined beam of light and diffused light (contact 30) can be produced.

Various modifications, as to location of 90 the lamps, contour and location of the reflectors and of the hood may be made without departing from the spirit and intent of the appended claims. Therefore, without limiting myself to the precise construction 95 shown and described,

I claim:—

1. A headlight comprising, a case, a concave main reflector in said case, a lamp in 100 said case and having the center of illumination thereof located on the axis of said main reflector, a second lamp in said case within the boundaries of said main reflector and the center of illumination thereof located away from said axis of the main reflector, and sub-reflectors co-operating with and facing said main reflector and both of said lamps; both of said lamps of equal illuminating power, and said reflectors arranged so that the illumination of the first 110 said lamp emits a beam of light from said headlight and that the illumination of said second lamp emits a diffused light from said headlight.

2. A headlight comprising, a case, a concave main reflector in said case and having an open front end interrupted by a sub-reflecter facing said main reflector, two lamps of substantially equal illuminating power in said case, both of said lamps 120 within the boundaries of said main reflector, the center of illumination of one of said lamps located on the axis of said main reflector to form the nucleus for a beam of light when the same is illuminating, the center of illumination of the other of said lamps located away from said axis of the main reflector to form the nucleus for a diffused light when the same is illuminating, and said sub-reflecter adapted to assist in 125 130

in the formation of said beam of light or of said diffused light or of both of said lights.

3. A headlight comprising, a case having an open end and an obliquely indented portion at the lower front end thereof, a main reflector mounted in said case and cut away at the lower front end thereof in conformity to said indented portion of said case, a sub-reflector on said indented portion of said case and over said cut away portion of said main reflector, a lamp in said case and the center of illumination thereof located on the axis of said main reflector, a second lamp in said case and the center of illumination thereof located away from said axis of said main reflector, a source of electricity for said lamps, and a switch means adapted to selectively connect said source of electricity with either one or with both of said lamps.
4. A headlight comprising, a case having an open end and an obliquely indented portion at the lower front end thereof, a main reflector mounted in said case and cut away at the lower front end thereof in conformity to said indented portion of said case, a sub-reflector on said indented portion of said case and over said cut away portion of said main reflector, a lamp in said case and the center of illumination thereof located on the axis of said main reflector, a second lamp in said case and the center of illumination thereof located away from said axis of said main reflector, a hood on the front of said case and over a portion of said open end thereof, a reflector in said hood, a source of electricity for said lamps, and switch means adapted to selectively connect said source of electricity with either one or with both of said lamps. 25 30 35 40

WILLIAM A. ROBERTSON.
